(57) **CLAIM**

The ornamental design for a removable cover for a modular mounting bracket, as shown and described.

DESCRIPTION

FIG. 1 is a perspective view of a removable cover for a modular mounting bracket;

FIG. 2 is a front view of the removable cover for a modular mounting bracket;

FIG. 3 is a rear view of the removable cover for a modular mounting bracket;

FIG. 4 is a right side view of the removable cover for a modular mounting bracket;

FIG. 5 is a left side view of the removable cover for a modular mounting bracket;

FIG. 6 is a bottom view of the removable cover for a modular mounting bracket;

FIG. 7 is a top view of the removable cover for a modular mounting bracket;

FIG. 8 is a perspective view of an alternative embodiment of a removable cover for a modular mounting bracket;

FIG. 9 is a front view of the alternative embodiment of the removable cover for a modular mounting bracket;

FIG. 10 is a rear view of the alternative embodiment of the removable cover for a modular mounting bracket;

FIG. 11 is a right side view of the alternative embodiment of the removable cover for a modular mounting bracket;

FIG. 12 is a left side view of the alternative embodiment of the removable cover for a modular mounting bracket;

FIG. 13 is a bottom view of the alternative embodiment of the removable cover for a modular mounting bracket; and,

FIG. 14 is a top view of the alternative embodiment of the removable cover for a modular mounting bracket.
